Primary Examiner — Catherine A Tuttle(74) *Attorney, Agent, or Firm* — Kirton McConkie; Brian Tucker(57) **CLAIM**

The ornamental design for a toy for infants or toddlers, as shown and described.

DESCRIPTION

FIG. 1 is a front perspective view thereof;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof; and,
FIG. 7 is a bottom plan view thereof.

The broken lines represent possible textures and bottom surface portions for the toy for infants or toddlers that form no part of the claimed design.

1 Claim, 7 Drawing Sheets(56)
